UNITED STATES PATENT OFFICE.

WALTER S. HUMPHREY, OF KANSAS CITY, MISSOURI.

OIL BURNER.

Application filed June 11, 1923. Serial No. 644,618.

To all whom it may concern:

Be it known that I, WALTER S. HUMPHREY, a citizen of the United States, residing at Kansas City, in the county of Jackson 5 and State of Missouri, have invented certain new and useful Improvements in Oil Burners; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention relates to oil burners and the primary object thereof is to provide an improved oil burner so constructed that the oil will be subjected to the action of an incandescent part of the burner as it is fed 20 from the vaporizing chamber, thereby insuring a complete gasifying of the oil with marked efficiency over those types of burners in which the oil is ignited before it is generated into a relatively dry gas.

25 In carrying out my invention I provide a base for the burner consisting of a material having a high heat resistance so that the base may be heated to practically incandescence, radiating intense rays of heat through 30 the vapor discharge from the generating chamber prior to having the gas ignited.

It is an important feature of the invention that the base be of such material that it will heat up to incandescence since it has 35 been found that the oil vapors burn with marked efficiency in an incandescent zone and it is also important that provision be made for eliminating or at least reducing the liability of carbon forming in the passages or

40 in the vaporizing chamber because where there is an accumulation of carbon, the efficiency of the burner is materially reduced.

In order to provide for more perfect combustion I have provided a mixing chamber in 45 which the heated or vaporized hydrocarbon is introduced into the mixing chamber and combined with air so that the fuel thus provided can be fed against the incandescent zone of the burner. The mixing chamber is 50 in the form of a nozzle, having an expansion zone so that the vaporized fuel may expand as it comes into contact with the air to effect a thorough co-mingling of the two constituents of the fuel. The fuel is fed against 55 the incandescent zone in the form of a blast

so that perfect combustion will take place and the vaporizing chamber is arranged to surround the incandescent zone or to be in sufficiently close proximity thereto so that there will be a thorough vaporization of the 60 hydrocarbon content of the fuel before it is mixed with the air.

There are other novel features of my invention, all of which will be specifically described hereinafter, reference being had to 65 the accompanying drawings, in which—

Fig. 1 is a perspective view of a burner constructed in accordance with my invention.

Fig. 2 is an enlarged, sectional view 70 through the burner mixing chamber and supply nozzle and the incandescent part, and

Fig. 3 is a longitudinal view of the air supply pipe, the gas priming nozzle being 75 shown in elevation.

Referring now to the drawings by numerals of reference:

1 designates a furnace which may be of any preferred construction. The furnace is 80 shown as being provided with a burner base 2, the burner base being in the form of a metallic ring having a groove 3 with refractory material in it. The ring carries a central refractory member 4 having a metal 85 oil pan 5 surrounded by a plurality of air inlet openings 6, the inlet openings being arranged in circular series. The pan 5 has an overflow port 7 in the side of the central air inlet pipe 7' connected to a pipe 8 which 90 discharges into a bucket or receptacle 9 to operate a valve 10 in the main oil supply line 11.

The receptacle 9 functions in a manner similar to that shown in my application 95 Serial No. 635,099, filed April 27, 1923 so that when the oil overflows to fill the bucket 9, the supply will be cut off in the pipe 11.

The oil pipe passes through the burner member 4 and discharges into a hollow ring 100 or manifold 12, which surrounds a cone-shaped block 13 of refractory material supported from the leg 4' of refractory material carried by the member 4 so that the pipe will be heat insulated from the 105 flame of the burner. The leg 4' co-operates with the leg 4'' to support the retort. The ring-shaped manifold 12 has an inverted U-shaped outlet pipe or arch provided with two legs 16 and 17 which discharge through 110

a nozzle 18 into a spherical expansion head 19, terminating in a depending constricted nozzle 20, which directs fuel against the cone-shaped block 13.

5 The head 19 constitutes a mixing chamber and it is supplied with air under pressure through a pipe 21 which, in turn, by an air pump 22 driven by a suitable motor 22'.

The pipe 21 is made up of a plurality of 0 sections with overlapping or slip joints so that the pipe sections can be readily assembled. The pipe 21 has a damper or valve 23 therein, by means of which the effective port area of the pipe 21 may be controlled. There is a gas priming pipe 24 15 adapted to discharge into the pipe 21 (see Fig. 3), the pipe 24 being adapted to be controlled by a valve 25 so that it can be normally closed, the valve 25 being unseated 20 only to prime the burner.

When the parts are assembled and the air pump or impeller 22' is operating, air may be forced through the pipe 21 into the head 19 to mix with the vaporized hydrocarbon. 25 The spherical form of the head or mixing chamber 19 is important since it allows for a thorough co-mingling and mixing of the hydrocarbon and air and since it is of sufficient size to allow expansion of the air and 30 fuel within it, thorough mixing will be insured. The form of the head is such that liability of carbon being deposited therein will be eliminated.

By providing the head of spherical form, 35 a construction is provided which insures a uniform flow of the combustible mixture in the desired direction; that is, toward the refractory cone, thereby resulting in combustion taking place in the center of the incandescent zone which prevents the burning 40 of the vaporizing ring or retort because there will be no liability of the flame being deflected over the retort.

In actual practice I prefer to locate the 45 nozzle 18 in the top of the head 19 so as to protect it from heat and to so locate it that its discharge end will be cooled by the introduced air fed from the pipe 21. The effect of this is that liability of carbon 50 forming in the nozzle 18 will be eliminated.

Since the vapor pressure through the nozzle 18 is in excess of the air pressure when the pump is idle, it will be apparent that if, 55 for any reason, the pump fails to function, the gas will siphon the air through the pipe, thereby permitting the burner to operate successfully with the additional air supplied through the openings 6 and with the air which passes through the material in 60 the space or groove 3. The material which fills the groove 3 allows air to pass through it because it is coarse enough to allow the passage of air. The purpose of placing the material in the space or groove 3 is to provide a muffler so that there will be no lia-

bility of a roaring noise due to the passage of air such as is common in certain types of burners.

As a refinement of my invention I prefer to construct the retort and the arch of copper because copper does not have an affinity for carbon. The copper gives off microscopic scales which are thrown off by the walls of the retort and the wall of the arch, permitting the scale and the liberated carbon to be thrown out through the burner head through the gas nozzle 18. If the gas nozzle is made of brass, there will be less tendency to scale because the brass is a harder material and since it may be provided with a smooth wall, the carbon and scales may pass through the constricted outlet or aperture 18', the size of which should preferably be about one-eighth inch diameter.

The pipe 11 is provided with a valve 26, controlled by an arm 27 which may be connected to the damper 23 so that the air admitted through pipe 21 can be proportioned with respect to the passage of oil fed through pipe 11.

It will be apparent from the foregoing that the device is simple in construction, that it may be readily set up and that a thorough co-mingling of the fuel constituents will be provided before the fuel is fed onto the incandescent zone and since the fuel comes in contact with the incandescent zone 13, it will be apparent that a thorough combustion can take place.

What I claim and desire to secure by Letters Patent is:

1. In an oil burner, a base comprising a ring-shaped member filled with loose material to admit air through the member, an oil pan within the ring, a centrally located refractory member above the pan, a support for said member, a ring-shaped retort above the base and about the refractory member, a hollow arch communicating with the retort, and a spherical mixing chamber communicating with the hollow arch and having a nozzle in line with the refractory member.

2. In an oil burner, a spherical air and vapor mixing chamber having a depending nozzle, a hydrocarbon vapor generating retort, a hollow arch communicating with the retort, the middle portion of the arch extending over the mixing chamber, a nozzle affording communication between the middle portion of the arch and the spherical air and vapor mixing chamber, the second nozzle having a restricted opening within the spherical air and vapor mixing chamber and located at the top thereof in line with the depending nozzle.

3. In an oil burner, a base, a ring-shaped retort above the base, a refractory member within the ring, a support for the refrac-

tory member, a hollow arch communicating with the retort, a spherical chamber above the member having a nozzle in line therewith, means for feeding air to the spherical chamber, and means affording communication between the hollow arch and the spherical chamber.

4. In an oil burner, a base, a conical member carried by the base, a ring-shaped retort about the conical member, an oil supply

pipe communicating with the retort, a hollow arch communicating with the retort, an air and vapor mixing chamber having a nozzle in line with the conical member, means for admitting air to the chamber, and means affording communication between the chamber and the arch. 15

In testimony whereof I affix my signature.

WALTER S. HUMPHREY.
